UNITED STATES PATENT OFFICE.

GEORGE A. MARSH, OF DIXFIELD, MAINE.

TIPPING-MACHINE.

1,111,162.

Specification of Letters Patent. Patented Sept. 22, 1914.

Application filed March 4, 1914. Serial No. 822,265.

To all whom it may concern:

Be it known that I, GEORGE A. MARSH, of Dixfield, in the county of Oxford and State of Maine, have invented certain new and useful Improvements in Tipping-Machines, of which the following is a specification.

My invention relates to can tipping machines such as are used in the canning industry for sealing the vent holes of the cans after the caps have been soldered in place.

The invention relates particularly to certain improvements in the construction of the tipping machine patented to me Aug. 6, 1912 and numbered 1,034,473 and the object 15 of the invention is to make the machine more compact and to provide means for more accurately adjusting the parts.

The machine covered by my former patent included a feeding mechanism for feeding 20 a line of cans, a tipping iron pivoted above the line of cans to a pivoted frame and means actuated by the passing can for swinging the pivoted frame to lower the tipping iron at the right instant to drop its 25 point into the vent hole of the can and to lift it again after it had been carried a limited distance by the movement of the can whereby the tipping iron would swing back to its normal position.

My invention may best be understood by 30 reference to the accompanying drawing, wherein is shown a tipping machine of the general character described with my improved construction applied thereto.

In the drawing, Figure 1 is a side elevation 35 of the machine, Fig. 2 is a rear elevation, Fig. 3 is a plan, Fig. 4 is a section on the line $\alpha\alpha$ of Fig. 3, Fig. 5 is a front elevation of the pivot for suspending the tipping 40 implement and its support. Fig. 6 is a vertical section through the same, and Fig. 7 is a detail of the guide for centering the tipping implement.

In the drawing like reference figures indicate like parts.

The tipping machine is usually applied to a conveyer having a movable bed consisting of a series of lags 1 traveling on stringers 2 and connected together by a sprocket 50 chain 3. A series of cans 4 are fed by the movable bed in a continuous line as they come from the capping machine. The tipping machine is secured by suitable means to the side of one of the stringers 2 and the 55 tipping iron 8 having a spindle 8^a is hung with a pivoted connection from a vertically

movable frame which is raised and supported by a spring and depressed by a lever actuated by the side of the passing can.

As here shown, the frame consists of a 60 rod 5 adapted to slide vertically in guides 6 and 7 positioned one above the other. The rod 5 is prevented from turning and is held steadily in position by a guide rod 10 parallel with the rod 5 and connected 65 with it at the upper end by a cross head 9. The lower end of the rod 10 passes through a guide 10' and a helical spring 11 surrounds the rod and provides the means for sustaining and lifting the entire frame including the tipping iron. The lower end of the spring 11 impinges on the guide 10' and the upper end rests against an adjusting nut 12 threaded on the rod. By screwing the 70 nut up or down the tension of the spring 75 may be regulated and the lifting power of the frame nicely adjusted.

The tipping iron 8 is suspended by its stem from the pivot 13 and the latter is carried by a horizontally adjustable rod 14 fitting in the crosshead 9, the rod being held in place by a set screw 15. The pivot is so secured to the end of the rod as to be vertically adjustable. As herein shown a vertical guide 18 is secured to the end of the 85 rod 14 and in this guide is a pivot block 16 carrying the pivot 13 to which the tipping implement is hung.

A screw 17 journaled in the guide 18 engages the block 16 and provides the means 90 for its vertical adjustment and a vertical rod 17^a secured to the guide 18 parallel with the screw 17 passes through the inner portion of the pivot block and serves to guide the same.

The adjustment of the tipping iron in the direction of the feed of the cans is secured by a V-shaped guide 19 adjustably secured to the end of a bracket 20 projecting out from the body of the machine. This guide 100 receives and centers the stem of the tipping iron as it swings back after tipping the can and its position determines the position of the tipping iron and enables it to be so adjusted that it will enter the vent hole 105 when the frame is depressed. The frame and the tipping iron are depressed by the force exerted by the passing can.

As here shown the rod 5 is depressed by a centrally pivoted lever 21, one end of which 110 engages a pin 22 set in a slot in the lower end of the rod. The opposite end of the

lever carries an antifriction roll 23 which bears normally against a bearing surface 24 formed on the pivoted arm 26. The arm 26 carries on its free end an antifriction roll 27 which is designed to contact with the side of each can as it passes by and to be forced outwardly thereby. As the arm 26 swings outwardly, the lever 21 is moved on its pivot point and its outer end depresses the rod 5. 5

10 The upper portion of the roll 27 is formed into an upwardly flaring flange which fits over the upper corner of the can and tends to hold it from tilting on its traveling bed. The arm 26 is prevented from swinging 15 too far inward when not in contact with a can by means of a hook 34 secured to the arm 26 and extending outward to engage the rod 28 which forms the pivot for the lever 21. 20

20 Lateral guides 29 are provided to hold the cans in line while they are passing the tipping mechanism and a double upper guide plate 30 is located so that the cans pass immediately beneath it, the cans being thereby prevented from tilting and getting out of position. The guide plate 30 is secured to the lower end of a guide rod 32 and the latter is adjustably secured in a bracket 31 fastened to the frame of the machine. The can is given a rotating movement as it passes the tipping mechanism by means of a horizontally disposed rubber tired roller 33 journaled in a swinging frame 38 and pressed inwardly against the 30 side of the passing can by a spring 35. 35

Rotation is given to the roll 33 by a pulley 36 which is fitted to a pulley not here shown and from which power is derived.

From what has been said the operation 40 of my improved machine may be readily understood. As the cans pass by, each can comes in contact with the roll 27 on the arm 26 and forcing it outward depresses the end of the lever 21 and the frame to which the 45 tipping iron is hung. The point of the iron enters the vent hole and, as the can moves along, it carries the tipping iron along with it far enough to seal the vent hole. The can is rotated by the roll 33 during 50 this operation insuring the even distribution of the solder in the vent hole. When the can has passed by, the arm 26 is released and the rod 5 and its connecting parts carrying the tipping iron are lifted 55 and the iron swings back to a bearing in the forked guide 19 where it remains until the next can comes along.

The mechanism for feeding solder to the 60 tipping iron which is no part of my present invention is not shown herein.

A tipping machine constructed as above described is simple and compact. It contains all the adjustments necessary to accurately place the tipping iron so that its 65 point will always strike in the vent hole.

It is self contained and can readily be connected to the side of the conveyer which carries the line of cans from the capping machine.

I claim:—

1. In a can tipping machine of the character described the combination of can feeding mechanism, a vertically slidable frame, vertical guides for said frame, a tipping implement pivoted to said frame, a spring for lifting said frame, a lever for depressing said frame and means actuated by the movement of the passing can for operating said lever to depress said frame. 70

2. In a can tipping machine of the character described, the combination of can feeding mechanism, a vertically slidable frame, vertical guides for said frame, a tipping implement pivoted to said frame, a spring for lifting said frame, a lever for depressing said frame, a pivoted arm connected with said lever to actuate the same and positioned to be acted upon by the side of the passing can. 80

3. In a can tipping machine of the character described, the combination of a can feeding mechanism for feeding a line of cans, a vertically movable frame, a tipping implement pivoted to said frame, a spring 95 for lifting said frame, a lever for depressing said frame, a pivoted arm connected with said lever to actuate the same, a horizontally disposed anti-friction roller on the end of said arm positioned to be acted upon by the side of the passing can, said roller having a flange on its upper end fitting over the edge of the can to hold the same down. 100

4. In a can tipping machine of the character described, the combination of a can feeding mechanism for feeding a line of cans, a vertically movable frame, a tipping implement pivoted to said frame, a spring 105 for lifting said frame, a lever pivoted between its ends and having one end engaging the frame to depress the same and having on the other end an anti-friction roll, a pivoted arm having a movable end positioned to contact with the side of the passing can and having a bearing surface positioned to contact with said antifriction roll. 110

5. In a can tipping machine of the character described, the combination of a can feeding mechanism for feeding a line of cans, a vertically movable frame, a horizontally disposed rod adjustably secured in the upper portion of said frame, a tipping implement pivoted at the end of said rod, a spring for lifting said frame, a lever for 120 depressing said frame and means actuated by the passing can for operating said lever to depress the frame. 125

6. In a can tipping machine of the character described, the combination of a can 130

feeding mechanism for feeding a line of cans, a vertically movable frame, a horizontally disposed rod adjustably secured in the upper portion of said frame, a pivot head carried by said rod, a pivot block movably secured to said head, adjusting screw for adjusting the position of said block, a tipping implement pivoted to said block, a spring for lifting said frame, a lever for

depressing said frame and means actuated 10 by the passing can for operating said lever to depress the frame.

In testimony whereof I have affixed my signature, in presence of two witnesses.

GEORGE A. MARSH.
